DESIGN FOR A COMBINED PORTABLE VACUUM CLEANER AND BLOWER OR SIMILAR ARTICLE

Tage G. Jonn, Chicago, Ill., assignor to Breuer Electric Mfg. Co., Chicago, Ill., a corporation of Illinois

Application August 20, 1936, Serial No. 64,489

Term of patent 14 years

To all whom it may concern:

Be it known that I, Tage G. Jonn, a subject of the King of Sweden and a resident of the city of Chicago, county of Cook, and State of Illinois, have invented a new, original, and ornamental Design for a Combined Portable Vacuum Cleaner and Blower or Similar Article, of which the following is a specification, reference being had to the accompanying drawings, forming a part thereof.

On the drawings:

Figure 1 is a side view of a combined portable vacuum cleaner and blower or similar article showing my new design.

Figure 2 is a side view looking at the left of the disclosure in Figure 1.

Figure 3 is a plan view of the same.

Figure 4 illustrates the suction unit, removed from the cleaner, as viewed from its discharge end, and in the normal position when used independently for either suction or blowing.

I claim:

The ornamental design for a combined portable vacuum cleaner and blower or similar article, as shown and described.

TAGE G. JONN.
